LOADBREAK CONNECTOR WITH PULLING EYE

Frederick Carl De Sio, Harrisburg, Pa., assignor to
AMP Incorporated, Harrisburg, Pa.

Filed Aug. 11, 1970, Ser. No. 24,646

Term of patent 14 years

Int. Cl. D13—03

U.S. Cl. D26—1

FIG. 1 is a perspective view of a loadbreak connector with pulling eye showing my new design;

FIG. 2 is a side elevation view thereof;

FIG. 3 is a plan view thereof;

FIG. 4 is a bottom view thereof;

FIG. 5 is a front elevation view thereof;

FIG. 6 is a rear elevation view thereof; and

FIG. 7 is a fragmentary rear elevation view thereof with the eye and its plate turned to an alternate position.

I claim:

The ornamental design for a loadbreak connector with pulling eye, substantially as shown and described.
